MACHINE FOR SALVAGING CARBONS

Wallace E. Cross, Detroit, Mich.

Application January 21, 1935, Serial No. 2,740

5 Claims. (Cl. 82—1)

This invention relates to apparatus for salvaging the carbon electrodes of arc lights, and particularly of picture projectors.

In operating the larger types of picture projectors, it has heretofore been the practice to discard the positive carbon electrodes when burned down to about one-third of their original length, because this is the approximate distance between the arc and a certain feed mechanism by which the electrodes are fed, both forwardly and rotatively. Since these electrodes cost between 40¢ and 50¢ apiece, it is apparent that the aforementioned practice involves quite an expensive waste.

An object of the invention is to provide a highly simplified machine or apparatus for turning a shoulder on the rear (or hard) end of a carbon electrode for such engagement by a tubular adapter as will permit the latter to maintain a flush relation with the main body of the electrode.

A further object is to so enclose the cutter of such a machine and to so seal the electrode engaging said cutter as to very positively prevent any escape from the machine of carbon particles and resultant detraction from the cleanliness of the projection room in which the machine would ordinarily be employed.

These and various other objects the invention attains by the construction hereinafter described, and illustrated in the accompanying drawing, wherein:

Fig. 1 is a view of the machine in axial vertical section.

Fig. 2 is a fragmentary vertical cross section of the machine, taken upon the line 2—2 of Fig. 1 and primarily showing an electrode-holding chuck.

Fig. 3 is another fragmentary vertical cross section, taken upon the line 3—3 of Fig. 1, and particularly showing the cutter.

Fig. 4 is a fragmentary section repeating a portion of Fig. 1, but showing the initial position of the cutter.

Fig. 5 is a perspective view of an electrode equipped with the adapter made applicable to the electrode by the described machine.

In these views, the reference character 1 designates the rectangular lower portion of a metal housing having a reduced rectangular upper portion 2 within which an annular cutter 3 is adapted to engage a carbon electrode 4 to form on the latter the shouldered and reduced end portion 5. Said cutter is preferably formed integrally and terminally upon a shaft 6 journaled in a bearing 7, which exteriorly projects from the portion 2 of

the housing. Adjacent to the bearing 7 there is mounted fast on said shaft a crank wheel 8 provided with the operating handle 9. In being rotated by the crank wheel, said shaft is adapted to be also slid into the housing from its position shown in Fig. 5 to that appearing in Fig. 1, for the purpose of feeding the cutter to the work. This feeding movement is limited by forming the shaft 6 with an annular slot 10, and engaging in said slot a screw 11 or other stop element carried by the bearing 7.

In axially opposed relation to the shaft 6, the portion 2 of the housing is formed with an opening threaded to receive an electrode-holding chuck. As illustrated, this chuck comprises a sleeve 12 having its inner end 13 enlarged and screwed into said opening, and a collet 14 in said sleeve for mounting the electrode 4, and accurately axially aligning it with the cutter. The collet is formed with a plurality of slits 15 extending longitudinally of and radially to the collet from its inner end for a major portion of its length, thus forming a number of flexible tongues 16 which may be contracted to firmly grip the electrode. The inner end of the collet is externally conically flared, as indicated at 17, to fit in a correspondingly flared terminal enlargement of the opening of the sleeve 12, so that by increasingly drawing the flared end portion of the collet into the sleeve, the tongues 16 are contracted to firmly clamp an electrode. Adjacent to the outer end of the sleeve 12, a nut 18 is threaded upon the corresponding end of the collet to provide for forcing the latter outwardly in the sleeve, to thereby effect inward flexing of the tongues 16, and said nut is preferably equipped with one or more radial operating handles 19. Rotation of the collet relative to the sleeve is prohibited by mounting in the sleeve a pin 20 or the like engaging in a key-way 21 formed in the collet.

In use of the described machine, the shaft 6, with its crank wheel 8, is initially outwardly shifted to the limit established by the stop screw 11, as shown in Fig. 5. The hard or unburned end portion of a carbon electrode is then inserted in the collet 14 until it engages the cutter 3. The nut 18 is then turned to cause a firm gripping of the electrode by the chuck. The shaft 6 is now rotated and is at the same time subjected to a slight axial pressure such as to feed the cutter against the electrode. Upon formation by the cutter of the desired reduced portion 5 of the electrode, further advance of the cutter is prohibited through bottoming of its in-

terior opening against the electrode, as Fig. 1 indicates.

The described machine may be easily adapted to operate upon electrodes of different thicknesses by providing several different sized chucks for alternative engagement with the housing 2.

To an electrode machined as described, there may be applied a tubular adapter 22 equal in exterior diameter to the electrode and interiorly adapted to fit snugly on the reduced end portion 5, such adapter preferably having one or both ends slit longitudinally as indicated at 23, to permit a slight resilient expansion of the adapter by the electrode to render the connection more firm. The increased length of the electrode imparted by the described adapter permits consumption of the electrode to a considerably greater extent than has heretofore been feasible, and consequently very materially reduces that portion of the electrode which must be eventually discarded.

It is a vital feature of the described invention that the adapter is applied to the unburned or hard end of the electrode, since this permits of the exact axial alignment of the electrode and adapter that is essential to practical use of the latter. The burned end of the electrode is ordinarily gradually tapered, due to exposure to the arc, and has lost its original regularity to an extent prohibiting accurate machining. Application of an adapter to the unburned end is further to be preferred, for the reason that this leaves the opposite end in condition for immediate efficient use, whereas a reversal end for end of the electrode for salvaging purposes would present to the arc an end requiring exposure thereto for at least several minutes before the arc could acquire a normal and steady brilliancy.

The invention is presented as including all such modifications and changes as come within the scope of the following claims.

What I claim is:

1. A machine for salvaging carbon electrodes comprising a support, a shaft rotatable and longitudinally slid able on said support, a common means for rotating and sliding said shaft, an annular cutting tool terminally mounted on said shaft, a sleeve coaxial with said shaft detachably mounted on said support in spaced relation to the cutting tool, a collet mounted in said sleeve and longitudinally slit to form with the sleeve

a chuck adapted to clamp a carbon electrode in coaxial relation with said cutting tool, means carried by said sleeve resisting rotation of said collet, means for effecting contraction of the collet, and means for limiting sliding actuation of said shaft. 5

2. A machine for salvaging carbon electrodes comprising a housing having a reduced upper portion, a shaft journaled and longitudinally slideable in a wall of said reduced portion, an annular cutter terminally mounted on said shaft 10 within the housing, a common means for rotating and sliding said shaft, a chuck mounted in an opposed wall of said housing coaxially with said shaft and mounted to clamp the carbon electrode in position for engagement by said cutter. 15

3. A machine for salvaging electrodes comprising a support forming a cutting chamber, a cutting tool within said chamber, a shaft carrying said tool, rotatable and longitudinally movable in a wall of said chamber, an electrode-holding 20 chuck mounted coaxially with the shaft in an opposite wall of said chamber, and a common means, exterior to said chamber for rotating the shaft and actuating it longitudinally.

4. A machine for salvaging carbon electrodes 25 comprising a support, an annularly grooved shaft rotatable and longitudinally slideable on said support, a common means for rotating and sliding the shaft, an annular cutting tool terminally mounted on the shaft, a chuck mounted on the 30 support in spaced relation and in axial alignment with the cutting tool and having a central axial opening for receiving a carbon electrode engaged by the chuck, and a stop element carried by the support and engaging in the annular groove of 35 the shaft to limit sliding actuation of the shaft.

5. A machine for salvaging carbon electrodes comprising a support, a shaft rotatable and longitudinally slideable on said support, a common means for rotating and sliding the shaft, an annular cutting tool terminally mounted on said shaft, a chuck mounted on the support in spaced relation and in axial alignment with said cutting tool, said chuck having a central axial opening for receiving a carbon electrode engaged by the chuck, and means upon the support for limiting sliding actuation of said shaft, said support forming a housing to receive cuttings, and the shaft and chuck being mounted in opposed walls of said housing. 45 50
